UNITED STATES PATENT OFFICE.

CLAUDE RORABECK, OF DAYTON, OHIO.

MANIFOLD FOR GAS-ENGINES.

1,190,592.

Specification of Letters Patent.

Patented July 11, 1916.

Original application filed January 2, 1915, Serial No. 126. Divided and this application filed April 14, 1915.
Serial No. 21,203.

To all whom it may concern:

Be it known that I, CLAUDE RORABECK, a citizen of the United States, residing at Dayton, in the county of Montgomery and State of Ohio, have invented certain new and useful Improvements in Manifolds for Gas-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in gas engines.

The invention contemplates the application to engines of the above type two explosive mixture converters, commonly termed carbureters, one for the use of the heavier grades of oil and the other for lighter grades such as kerosene, and it further contemplates the application of a manifold which is utilized in connection with both carbureters. For example, when it is desired to run the engine with gasolene, as when starting the engines, the supply of kerosene to the carbureter is shut off, but when the engine has become sufficiently heated the supply of gasolene to the other carbureter is shut off and the kerosene carbureter is supplied. In one case, to-wit, when the engine is being run on gasolene, the gasolene and air is subjected to the heat of the exhaust and in that case the valves located in the manifold admit the explosive mixture from the manifold to the crank case and thence to the compression end of the cylinder. In the other case, to-wit, when the kerosene carbureter is in use, the valves in the manifold admit air to the crank case from the manifold. The manifold provides for the intake and exhaust. The air used in the formation of the explosive fluid in both cases is preheated from the exhaust and reheated in the manifold before entering the cylinder. To these ends the exhaust passage, intake passage, air and water passages, are combined in the manifold and the intake passage is subject to the heat of the exhaust as will be hereinafter more particularly described. The features embodying the subject matter of the descrip-

tion to follow and embraced in the claims is 55 divided from my pending application, Serial No. 126, filed January 2, 1915.

Referring to the accompanying drawings, Figure 1 is a lateral vertical section through one cylinder of a two-cycle gas engine with 60 my improvements applied thereto; Fig. 2 is a section on the line 2—2 of Fig. 1; Fig. 3 is a section on the line 3—3 of Fig. 2; Fig. 4 is a top plan view of the manifold with parts broken away to show the passageway for 65 the cooling medium; Fig. 5 is a section on the line 5—5 of Fig. 3; Fig. 6 is a section on the line 6—6 of Figs. 2 and 3; and Fig. 7 is a section on the line 7—7 of Fig. 1.

Throughout the specification and drawings, similar reference characters represent corresponding parts both in the description and drawings.

Referring more particularly to the drawings, 8 represents the crank case of an engine upon which are mounted cylinders 9. Reciprocatingly mounted within each cylinder 9 is a piston 10 connected to a crank 11 by a rod 12 in a well known manner. Each cylinder 9 has a head 13 provided with a 75 priming cock 14, and with any well known form of ignition device 15, and a water-cooling jacket 16. The air for supporting the portion of the fuel in the cylinder is previously compressed within the crank case 80 and is conducted into the cylinder 9 above the piston through lower and upper side ports 17—17' in the cylinder wall and a port 18 in the side of the piston. In order to prevent the top face of the piston 10 becoming overheated, the said piston is provided with a horizontal wall 19 which forms a cross passageway 20 on the under side of the top face of said piston. The air or mixture when passing from the crank case to the 85 cylinder passes through the passageway 20 and along the under side of the top of the piston 10 and serves to maintain the face of the piston at a reduced temperature. The cylinder-head 13 is provided with a cooling 90 jacket 21 which connects with the cooling jacket 16 around the sides of the cylinder through ports 22. The said head 13 is also provided with an air space 23 which lies between the head 13 and the cooling jacket 21. 95 The said air space 23 may or may not be open to the atmosphere and the same is instrumental in maintaining a desirable tem-

perature in the cylinder-head. Each cylinder 9 is provided with exhaust ports 24 which communicate with a passageway 25 of a combined exhaust and intake manifold 26. 5 The passageway 25 is closed at one end and may be connected with an exhaust pipe (not shown) at the other end 27, shown in Fig. 2. The air for supporting combustion is drawn into the crank case 8 through down 10 passage 28 in said cylinder 9. The entrance of air into the passage 28 is controlled by valve 29 on stem 30 slidably mounted in bearings 31 of valve casing 32, said valve being of the automatic type with spring 45. 15 The said valve casing 32 is mounted in a pocket formed by the wall 33 of the manifold and is provided with side port 34 which communicates with a passageway 35 which lies below and to one side of the exhaust 20 passageway 25, said passageways 25 and 35 being separated by a wall 36, shown in Fig. 3. The passageway 35 is provided with a centrally disposed opening 37 which connects with a gasoline carbureter 38 by means 25 of a curved tube 39. The said gasoline carbureter, which may be of any well known type, receives the air for forming the explosive mixture through a tube 40.

To preheat the air from the exhaust of 30 the engine before it is introduced into the carbureter, the manifold 26 is provided with a passageway 41 which communicates with the tube 40 through a centrally disposed opening 42. The said passageway 41 surrounds the exhaust passageway 25 and is 35 separated from said exhaust passageway by a wall 43, as shown in Fig. 5. The said passageway 41 communicates with the atmosphere through ports 44 at each end of the 40 manifold 26, shown in Fig. 2. By thus constructing the manifold, the air and mixture are previously heated by the exhaust gases and preheated before being introduced into the cylinder, and thus a more efficient combustion is obtainable. 45

When it is desired to run the engine on one cylinder and at reduced power, one of the valves 29 may be maintained closed by the following means: The said valve 29 is 50 provided, as before stated, with spring 45 which moves it to and maintains it in a closed position. The said spring 45 abuts at one end against a spool-shaped head 46 on the stem 36 of said valve. The said spool 46 is adapted to be engaged by swinging pawl 47 controlled by a thumb-screw 48. When pawl 47 is placed in engagement with its spool 46, valve 29 will be prevented from opening thereby placing the cylinder 29 out 55 of operation. The cooling water from the cylinders may be introduced into the jacket 60 through a conveniently located port 49, shown in Fig. 7. The water passes thence upwardly through the port 22 into the jacket 65 21 of the head 13 and thence downwardly

through port 50 into a passageway 51 along one side of the cylinder. The said passageway 51 communicates with a further passageway 52 which lies along the top of the manifold 26. The passageway 52 is formed 70 by the division wall 43, the outer casing of the manifold, and a partition wall 53, shown in Fig. 5. At one end of the manifold 26, the passageway 52 turns downwardly and is provided with an outlet 54 to which an exhaust pipe (not shown) may be connected. In order to cool the exhaust gases in the passageway 25 after they have passed out of the manifold, said manifold is provided with an opening 55 which communicates with the 80 water passageway 52 and the exhaust passageway 25. The opening 55 is controlled by a valve 56 mounted in a casing 57 in the top of the manifold. The valve 56 is instrumental in permitting water to be introduced into the exhaust pipe to cool the exhaust gases and to diminish the noise incidental to the exhaust. 85

In the above description, the engine is described as running on gasoline; means, however, are provided for operating the same on kerosene as follows: The engine cylinder 9 is provided with lower and upper ports 17 and 17' in the side thereof, as before stated. These ports communicate with a carbureter chamber 58, 17 being an air outlet port to said chamber 58 from the piston, and port 17' being an inlet port from the carbureter chamber 58 to the engine cylinder above the piston. Mounted along the side 90 of said cylinder adjacent to the chamber or passageway 58 is a kerosene carbureter 59 provided with a jet 60 which lies within the passageway 58. The carbureter 59 may be of any well known type. The kerosene at the jet 60 is vaporized by the heated air that passes through the manifold and the passage 20 in the piston head. The air is heated in the passages 41 and 35. For example, the air is preheated in passage 41 and reheated in passage 35, and receives a final heat in the passage 20. When it is desired to run the engine on gasoline, for example, as when starting and heating the engine, the supply of kerosene to the carbureter 59 is shut off, but, after the engine has become sufficiently heated to run on kerosene, the supply of gasoline to the carbureter 38 is shut off and the carbureter 59 is supplied with kerosene. 105 110 115 120

Having described my invention, I claim:

1. In an explosive engine, the combination with a crank case and a cylinder mounted thereon, of a manifold having a series of integrally united walls forming an intake passage, an exhaust passage surrounding two sides of said intake passage, air and water passages inclosing a side and the top of the exhaust passage, a carbureter communicating with said intake passage, and an ex- 125 130

terior pipe forming a medium of communication between said air passage and the carbureter.

2. In an explosive engine, a crank case, a cylinder mounted on said crank case having exhaust ports, and a carbureter opening in a side thereof, a kerosene carbureter mounted over said opening and delivering explosive fluid thereto, a piston in said cylinder controlling said carbureter opening, said piston having a passage forming a communication between the crank case and said carbureter opening, a manifold mounted on the side of said cylinder opposite said kerosene carbureter, having an intake passage, an exhaust passage communicating with the

exhaust ports of the cylinder, an air passage partly inclosing said intake and exhaust passages and communicating with the atmosphere, a gasoline carbureter communicating with said intake passage, and an air tube exterior to the manifold and extending from the air passage to said last named carbureter, the said cylinder being provided with a passage connecting the intake of the manifold with the crank case. 20
